CONVERSION OF HYDROCARBONS

Theodore W. Nelson, Woodbury, Henry D. Noll,
Wenonah, and Thomas P. Simpson, Woodbury,
N. J., assignors to Socony-Vacuum Oil Com-
pany, Incorporated, a corporation of New York

Application October 9, 1942, Serial No. 461,444

6 Claims. (Cl. 196—49)

1

This invention has to do with the conversion of petroleum hydrocarbons of gas oil boiling range to aviation fuels of exceptional quality.

There are several methods for the determination and expression of the anti-knock rating of aviation fuels. Typical methods are those of Cooperative Fuel Research Committee commonly known as the CFR. Those of one kind, of which method AFD-1C is typical, compare the tested fuel and a standard under conditions of lean mixture where the tendency to knock is most pronounced. A more recently adopted method compares under conditions more nearly related to maximum demand performance. This latter, the "rich mixture anti-knock" rating, method AFD-3C, sometimes called the "super-charged aviation" method is determined by comparisons of tested fuel and a reference fuel in the same engine, at the fuel-air ratio giving peak power on the reference fuel. The two methods are not comparable, being measures of basically different operating characteristics. Two fuels of the same AFD-1C rating may be widely different under AFD-3C rating. The AFD-3C rating method is intended to more closely reproduce actual operating conditions and reflect action of fuel when the engine is called upon for maximum power output.

It is well known that aviation base stocks may be prepared by subjecting petroleum material of gas oil nature, boiling in the range 400°-750° F. to catalytic cracking in vapor phase in the presence of solid adsorptive catalytic material, and then reprocessing the gasoline so produced under similar but more rigorous conditions, and separating from the product, material meeting the aviation boiling range specifications, namely with a 90% ASTM boiling point such that when the product is blended with alkylate or other agents, the 100 octane blend meets existing specifications.

While these materials form quite acceptable aviation fuels, when evaluated by the AFD-1C and similar methods, they are less valuable, i. e., require more alkylate, tetra ethyl lead, etc., to

2

be acceptable when measured by the AFD-3C method. For example, a given product of two pass operation may be blended 60-40 with a certain alkylate and with 4 cc. of lead to make a 100 rating by AFD-1C, but would have an AFD-3C rating of only S-1+0.6 cc., that is a rating equal to reference fuel #1, plus 0.6 cc. lead, where the present requirement to be met would be AFD-3C of S-1+1.0 cc. The requirement could be met by using a blend of 40% fuel and 60% alkylate, (alkylate in both cases rating as AFD-3C of S-1+3.0 cc., but obviously requiring more than twice as much alkylate to blend off a given amount of base fuel.)

- 15 This invention is based upon the surprising discovery that by proper handling of the materials from second pass operation in a further catalytic cracking, base fuels of exceptionally high AFD-3C rich-mixture rating can be produced, and it has for its object the provision of an operating method whereby such production can be achieved, leading directly to fuels of markedly increased capability with simultaneous savings of alkylate and similar materials.
- 20 In accordance with this invention, materials from the second pass catalytic cracking of catalytic gasoline, which materials are of higher boiling point than aviation gasoline, may be subjected to third pass cracking to yield a product within the aviation boiling range, which, with 4 cc. lead, will have an effective AFD-3C rating of S-1+6 cc. lead and higher. The process may be carried out by non-recycle third pass cracking of the selected material, by recycling the same material to the second pass operation in addition to the normal feed thereto, or by recycle cracking to total consumption of the selected material alone in a third pass operation.

As an example of the surprising efficacy of this operation, the tabular data below show the properties of aviation gasoline produced by taking the naphtha, heavier than gasoline, produced from two pass treatment, and again cracking it, as compared with the aviation gasoline produced by two pass operation.

Table I

Properties of Aviation Gasoline	Produced by—	
	Non-Recycle Crack- ing of Second-Pass Naphtha	Second-Pass Process- ing of First-Pass Gaso- line
Gravity, °A. P. I.....	50.4.....	61.0.....
Acid Heat, °F.....	10.....	6.0.....
Acet. (5 hr.) gum, Mgs./100 cc.....	6.....	9.0.....
Distillation ASTM, °F.:		
I. B. P.....	99.....	102.....
10% Vol.....	139.....	133.....
50% Vol.....	238.....	196.....
90% Vol.....	283.....	277.....
E. P.....	317.....	306.....
Rec. Per cent Vol.....	98.5.....	98.0.....
Octane Rating AFD-1C:		
cc. T. E. L.—		
0.....	86.4.....	79.6.....
3.....	99.4.....	95.3.....
4.....	Isooctane + 0.03 cc. T. E. L.....	98.7.....
100 O. N. Blend (4 cc. T. E. L.):		
Per cent Alkylate Req'd.....	0.....	20.....
AFD-3C Rating.....	S-1+6.0 cc. T. E. L.....	S-Z+1.5 cc. T. E. L.....

Probably the most striking thing apparent from the above comparison of the two fuels is the AFD-3C rating of the two fuels in contrast to their AFD-1C rating. Both fuels, when mixed with 4 cc. of lead give fuels of about 100 octane rating. Yet, under rich mixture conditions, the second pass aviation product, with 4 cc. of lead and in an 80-20 mixture with alkylate, gives a rating of only S-1+1.5 cc. while the third pass product of this invention, with 4 cc. lead, but without alkylate, has a rating of S-1+6.0 cc. When total recycling is employed in the third pass operation, the aviation gasoline product, with 4 cc. lead has an AFD-3C rating of S-1+>10 cc.

The steps utilized in arriving at this product are as follows: First, a gas oil of 720° F. end point of Coastal-Mirando origin, was cracked in vapor phase in a static bed catalytic cracking at a space velocity of 1.2 at 32 p. s. i. gauge and 830° F. to yield a first pass gasoline of about 400° F. end point. This cracking may be varied in temperature between about 800° F. and 900° F., and in pressure between 0 p. s. i. gauge and 75 or so p. s. i. gauge, and at space velocities of at least about 0.25, dependent upon the stock being handled, upon the activity of the catalyst, the method of handling—i. e., whether static bed of catalyst or continuously renewed catalyst, etc., as is well known. The gasoline so produced was then re-processed, in this instance being treated in a static bed, at 40 p. s. i. gauge and 835° F., and at a space velocity of 0.82, these conditions being appreciably more rigorous than those of the original. This second pass processing of gasoline boiling material will normally be conducted within the same broad temperature and pressure ranges as cracking, but at conditions somewhat more rigorous than the corresponding cracking. The aviation gasoline boiling point product of this second pass is that material described in the right hand column of Table I. The second pass product heavier than this, which was used as the charge in the third pass operation, and the following properties:

Second pass heavy naphtha

	Res. percent.....	1.0

This material was cracked at a temperature of 30 850° F., pressure of 50 p. s. i. and space velocity of 1.0. Here, while being more rigorous than second pass conditions, the temperature and pressure will be within the same broad general ranges. Appropriate conditions for second pass 35 operation and third pass operation both, like the first pass operation, will vary somewhat for the activity of the catalyst and method of contacting catalyst, as do the first pass operating conditions, but variations arising from the original 40 charge stock will tend to be ironed out to a greater degree in these subsequent pass operations.

The third pass operation may be conducted in 45 several ways. The first and simplest method is a single or once through operation upon the second pass heavy naphtha alone. This is the method used in the operation from which exemplary data was taken. Likewise a most highly anti-knock product can be gotten by a separate 50 operation utilizing as fresh charge the second pass heavy naphtha, and recycling to that operation the naphtha heavier than aviation cut produced therein. This operation, when carried out as an ultimate recycle, i. e., recycling enough to 55 consume all fresh charge and producing no side cut or drag in substantial amount, will give product of even higher rating than that shown. Another method for obtaining somewhat similar results consists of recycling the second pass heavy 60 naphtha during the second pass processing, and deriving from that second pass operation, a product which combines the normal second pass aviation cut and the aviation cut produced by re-cracking the second pass naphtha.

65 For a more complete understanding of the invention reference is made to the accompanying drawing, which is illustrative only and wherein the single figure is a diagrammatic flow sheet illustrating one arrangement of catalytic cracking and fractionating equipment wherein the process contemplated herein may be practiced.

In the drawing, numeral 1 indicates a heater to which gas oil is charged through the inlet pipe 2. The heated vapors leaving the heater 1 under the temperature and pressure conditions hereto-

fore indicated are conducted through a conduit 3 into a catalytic reactor 4 where the vapors are cracked in the presence of a solid adsorptive catalytic material. The catalytically-cracked product leaving the reactor 4 is delivered through conduit 5 into a fractionating step illustrated by the fractionator 6 which is shown as being provided at its top with a gas outlet 7 and at its bottom with an outlet 8 through which residuum is rejected from the system. The fractionator is also shown as being provided with a suitably-located plate or tray section 9 and draw-off connection 10-10' through which a recycle material may, if desired, be recycled through the first pass cracking operation practiced in heater 1 and reactor 4. Control of this recycle is shown as being effected by valves 11 and 11'.

The first pass naphtha hereinabove referred to is shown as being withdrawn from the fractionator through conduit 12. This first pass naphtha which constitutes the charge for the aforesaid second cracking operation carried out in heater 14 and catalytic reactor 15 is a fraction of the general nature of motor gasoline including material boiling up to the range 400-450° F.

In the second pass cracking operation the first pass naphtha vapors are conducted from heater 14 to reactor 15 through conduit 16, and in this cracking operation, as aforesaid, the vapors are cracked in the presence of a solid adsorptive catalytic material in reactor 15 under conditions more rigorous than those existent in the first cracking operation carried out in heater 1 and reactor 4.

The product of the second pass operation is shown as being conducted from reactor 15 through conduit 17 to a fractionating step illustrated by fractionator 18, which is shown as being provided with top and bottom outlet connections 19 and 20 for the discharge of gas and residue, respectively. The fractionating step illustrated by fractionator 18 is designed and operated so as to provide a gasoline cut of end point suitable for aviation fuel (in the approximate range of 300-325° F.), which cut is shown as being withdrawn from the fractionator 18 through conduit 21 as "2nd pass aviation gasoline." Also, as previously pointed out, this fractionating step is designed and operated so as to provide second pass heavy naphtha which is shown as being withdrawn from the fractionator 18 through conduit 22. This second pass heavy naphtha, as indicated by the typical specifications given hereinabove, is a fraction of relatively-narrow boiling range comprising material heavier than the aviation gasoline cut (withdrawn through conduit 21) but containing no substantial quantity of material boiling above 488° F., and it is this relatively-narrow boiling range heavy naphtha fraction which is re-cracked to form the high-quality aviation gasoline hereinabove referred to.

As aforesaid, there are several alternative procedures for effecting this re-cracking or third pass operation. The preferred procedure is to conduct the second pass heavy naphtha from conduit 22 through conduit 23 and valve 24 into a third cracking stage shown as being comprised of heater 25, conduit 26 and catalytic reactor 27. In this third pass cracking operation the second pass heavy naphtha is cracked in the presence of a solid adsorptive catalytic material in reactor 27 under conditions more rigorous than those existent in the second pass operation. The cracked products from this third cracking op-

eration are conducted through conduit 28 to a fractionating step, represented by fractionator 29, shown as being provided with conventional gas and residuum outlets 29g and 29r. This fractionating step is designed and operated so as to separate a gasoline fraction having an end point (in the approximate range of 300-325° F.) suitable for use as aviation gasoline, which fraction is shown as being withdrawn from the fractionator 29 through conduit 30 as "3rd pass aviation gasoline." It is this fraction which has been hereinabove identified as possessing the highly desirable properties of low acid heat and high rich mixture performance.

The 2nd pass aviation gasoline and the 3rd pass aviation gasoline may be withdrawn from the system as independent products through valved connections 21' and 30', or they may be blended in any suitable manner as through valved conduits 31 and 32 to form the desired low acid heat, low end point, high rich mixture anti-knock fuel.

In connection with the third pass operation just described, one desirable alternative or modification is to so design and operate the fractionating step as to collect a heavy naphtha fraction, which is shown as being collected at 33 in fractionator 29. This third pass heavy naphtha is conducted through conduits 34 and 35 (provided with suitable valves 34' and 35') to the inlet 23 of the heater 25 where the third pass heavy naphtha is recycled through the third pass cracking operation with the second pass heavy naphtha.

Another alternative operation for effecting re-cracking of the second pass heavy naphtha is to recycle same through the second pass cracking operation comprised of heater 14 and catalytic reactor 15. For the purpose of carrying out this last-mentioned alternative the conduit 22 is shown as being provided with an extension 22' the use of which is controlled by valve 37. Thus, by closing valve 24 and opening valve 37, the second pass heavy naphtha may be recycled through the second pass cracking step with first pass naphtha and the aviation gasoline product withdrawn from the system at 21.

We claim:

1. A method for the production of aviation gasoline which comprises the steps of: cracking a gas oil in vapor phase at temperatures in the range of 800-900° F. in the presence of a solid adsorptive catalytic material, segregating from the products of such cracking operation a first pass naphtha of the general nature of motor gasoline, subjecting said first pass naphtha to a second cracking operation under more rigorous conditions than those existent in said first pass and in the presence of a solid adsorptive catalytic material, segregating from the products of said second cracking operation a second pass heavy naphtha comprising material boiling above the range of aviation gasoline but containing no substantial quantity of material boiling above 488° F., subjecting said second pass naphtha to a third cracking operation in the presence of a solid adsorptive catalytic material and under conditions more rigorous than those existent in said second cracking operation, and segregating from the product of said third cracking operation a gasoline product of aviation fuel end point.

2. A method for the production of aviation gasoline which comprises the steps of: cracking a gas oil in vapor phase at temperatures in the range of 800-900° F. in the presence of a solid ad-

sorptive catalytic material, segregating from the products of such cracking operation a first pass naphtha of the general nature of motor gasoline, subjecting said first pass naphtha to a second cracking operation under more rigorous conditions than those existent in said first pass and in the presence of a solid adsorptive catalytic material, segregating from the products of said second cracking operation a second pass heavy naphtha comprising material boiling above the range of aviation gasoline but containing no substantial quantity of material boiling above 488° F., subjecting said second pass naphtha to a third cracking operation in the presence of a solid adsorptive catalytic material and under conditions more rigorous than those existent in said second cracking operation, segregating from the product of said third cracking operation a gasoline product of aviation fuel end point and a third pass heavy naphtha; and recycling said third pass heavy naphtha to said third cracking operation.

3. A method for the production of aviation fuel of low end point, low acid heat and high rich mixture anti-knock rating which comprises the steps of cracking gas oil in vapor phase in the presence of a solid adsorptive catalytic material and segregating from the products of such cracking a first pass naphtha including material having an end point not less than about 400° F. and not greater than about 450° F., subjecting said first pass naphtha to cracking temperatures and pressures in the presence of solid adsorptive catalytic material, segregating from the products of said second pass a gasoline cut of end point suitable for aviation fuel and a second pass heavy naphtha comprising materials heavier than said gasoline cut but containing no substantial quantity of materials boiling above about 488° F., and subjecting said second pass heavy naphtha to cracking temperatures and pressures in the presence of solid adsorptive catalytic material under cracking conditions more rigorous than the cracking conditions existent in said second pass operation to produce a gasoline product of aviation fuel end point and substantially high rich mixture rating.

4. A method for the production of aviation fuel of low end point, low acid heat and high rich mixture anti-knock rating which comprises the steps of cracking gas oil in vapor phase in the presence of a solid adsorptive catalytic material and segregating from the products of such cracking a first pass naphtha including material having an end point not less than about 400° F. and not greater than about 450° F., subjecting said first pass naphtha to cracking temperatures and pressures in the presence of solid adsorptive catalytic material under cracking conditions more rigorous than those existent in the first pass operation, segregating from the products of said second pass a gasoline cut of end point suitable for aviation fuel and a second pass naphtha comprising materials heavier than said gasoline cut but containing no substantial quantity of materials boiling above about 488° F., subjecting said second pass heavy naphtha to re-cracking in the presence of solid adsorptive catalytic material under cracking conditions more rigorous than those existent in said second pass operation, and segregating from the products of the third pass operation a gasoline product of aviation fuel end point.

5. A method for the production of aviation gasoline which comprises cracking a petroleum hydrocarbon material of gas oil boiling range in vapor phase in the presence of solid adsorptive catalytic material, segregating from the products of such cracking a first pass naphtha of the general nature of motor gasoline, subjecting said first pass naphtha to a second cracking operation in the presence of solid adsorptive catalytic material, segregating from the products of said second cracking operation a second pass heavy naphtha comprising material boiling above at least about 300° F. but containing no substantial quantity of material boiling above about 488° F., subjecting said second pass heavy naphtha to a third cracking operation in the presence of solid adsorptive catalytic material under the cracking conditions more rigorous than those existent in said second cracking operation, and segregating from the products of said third cracking operation a gasoline product of aviation fuel end point.
6. A method for the production of aviation gasoline which comprises cracking a petroleum hydrocarbon material of gas oil boiling range in vapor phase in the presence of solid adsorptive catalytic material, segregating from the products of such cracking a first pass naphtha of the general nature of motor gasoline, subjecting said first pass naphtha to a second cracking operation in the presence of solid adsorptive catalytic material, segregating from the products of said second cracking operation a second pass heavy naphtha comprising material boiling above at least about 300° F. but containing no substantial quantity of material boiling above about 488° F., subjecting said second pass heavy naphtha to a third cracking operation in the presence of solid adsorptive catalytic material under cracking conditions more rigorous than those existent in said second cracking operation, segregating from the products of said third cracking operation a gasoline product of aviation fuel end point and a heavy naphtha fraction, and recycling said third pass heavy naphtha fraction to said third cracking operation.
